UNITED STATES PATENT OFFICE.

IDA SCHMIDT MARVIN, OF DETROIT, MICHIGAN.

FUNERAL-CAR.

1,072,864.

Specification of Letters Patent.

Patented Sept. 9, 1913.

Application filed July 27, 1910. Serial No. 574,061.

To all whom it may concern:

Be it known that I, IDA SCHMIDT MARVIN, a citizen of the United States, residing at Detroit, county of Wayne, State of Michigan, have invented a certain new and useful Improvement in Funeral-Cars, and declare the following to be a full, clear, and exact description of the same, such as will enable others skilled in the art to which it pertains to make and use the same, reference being had to the accompanying drawings, which form a part of this specification.

My invention relates to funeral cars, and while designed to be applied to motor cars or self-propelling or self-operating cars, yet may be used with trolley cars running on tracks as will be obvious from the following description.

It consists in the various arrangements and combinations hereinafter pointed out and claimed.

In the drawings:—Figure 1, is a perspective elevation of the car containing my improvements and showing the compartment in which it is intended to carry the casket open for illustrative purposes. Fig. 2, is a cross sectional view on line 2—2 of Fig. 1. This illustrates a side opening on the left-hand side of the car looking forward. Fig. 3, is also a general cross sectional view on the line 2—2 of Fig. 1, but modified by showing an opening upon the right-hand side of the car looking forward. The remaining figures are drawn with reference to the side opening of the car upon its left-hand side looking forward or on the right-hand side of Fig. 2, it being obvious that the mode of operation is not changed by changing sides. Fig. 4, is a plan view of the casket platform and compartment with the casket turning at right angles for the purpose of removing it. Fig. 5, illustrates the mechanism for turning the casket and showing the casket in dotted lines as turned at right angles to the car. Fig. 6, illustrates the same mechanism, but also illustrates the movable platform upon which the turn-table and casket rests, and being a partial longitudinal section of the car drawn on the line 3—3, Fig. 4. Fig. 7, illustrates means for raising the casket when in position, and carried by the platform upon which it rests, which platform in turn is mounted upon the rotatable turntable, which again in turn is mounted upon the

said moving platform illustrated in Fig. 6. Fig. 8, is a plan view of the mechanism illustrated in Fig. 4, with the casket and platform upon which it rests omitted.

Similar letters refer to similar parts.

In the drawings, A, represents the framework and body of the car, which, as already stated, may be of any convenient size and driven by any form of power, whether electric, gasoline engine or by trolley. As shown it is driven by a self-contained motor which enables the car to run upon ordinary streets without tracks. The car proper is divided into three compartments. B, is the motorman's compartment; C, the passenger compartment, which may be entered from the rear, as suggested in the drawings; or may be from the side if desired; D, is the compartment for the casket and my invention resides in the arrangement and combination of mechanism contained in this compartment. The compartments C and D, are arranged to communicate by means of ordinary doors, (which may be either sliding or swinging), as shown at d, d.

E, is a casket illustrated in the ordinary position in the car it would ordinarily occupy while in transit. This casket rests upon a compound base which is partially illustrated in Figs. 2 and 3, and more fully illustrated in detail in Figs. 5 and 6.

G, represents the floor proper of the car; upon this in a fixed position is a base H, which extends longitudinally of the car and substantially of the length of the casket, as shown in Fig. 6 and has at each end a cross track H¹, carrying friction rollers h, h, as illustrated in Figs. 5 and 6, and also illustrated on a smaller scale in Figs. 2 and 3. Upon this track rests another platform or base H², slightly shorter than the base H, its ends resting upon the rollers h, h. This sub-base H², carries a circular flanged track f¹, somewhat smaller than another circular track f, inverted over it, the edges of the flanged iron of the latter encircling the flange of the track f¹; a fairly close fit is intended to be made at this point between these two tracks so as to prevent lateral or side motion. A table or platform F, upon which the casket directly rests is rigidly fastened to and supported by the circular track f, as illustrated. By this construction the platform F can be turned at right angles or at any other angle desired to the sub-platform H². A brake block J,

shown in Fig. 6, with means for pressing it up against the track f is provided so as to enable the platform F , carrying the casket to be fixed at any position whether 5 longitudinal of the car or at right angles thereto as shown in Fig. 4, and also preventing vibration. Of course, on releasing the brake, which may be done with screw-handle j , the casket can readily be turned. 10 If desired friction rollers or a groove with balls may be interposed between the two circular tracks and thus lessen the friction.

In Figs. 7 and 8, I have shown means for raising the platform F , as a modification of 15 the structure shown in Figs. 5 and 6, which consists in the insertion of another platform N , below the floor H^2 ; between this platform N and the platform F^1 is interposed a pair of lazy-tongs arrangements, as illustrated in Fig. 7, of the familiar type thereof. This consists of two right and left screws S , S^1 , one at each end working in 20 nuts adjacent to the central joints of a three-bar lazy tongs. It is obvious that by actuating the winch the screws may be rotated and thus the nuts S^3 , S^4 , in which they actuate can be either drawn together or separated. If drawn together they force 25 upward at each end the platform H , and its load. A reverse motion of the winch drops the lazy-tongs down until substantially no elevation exists more than the thickness of the parts necessary to inclose 30 the lazy-tongs. It is obvious that curtains 35 may be placed upon this lazy-tongs arrangement and which, when the casket is dropped, are folded up and out of the way and yet when raised would inclose the mechanism so that it would not be observed; for the sake 40 of clearness these curtains are omitted.

In order to separate the casket space from that compartment of the car on either side thereof, I place two drop curtains or roller shades K , K , which may be raised or 45 lowered by means of the rollers K^1 , K^1 , but as these shades or curtains have nothing in themselves that is novel they do not constitute any part of my invention.

The platform H^2 , (Fig. 7) and its tracks 50 or the platform H and tracks H^1 (Fig. 6) carry friction rollers engaging in appropriate shaped angle irons. Either platform joins and is continued by a movable side of the car H^3 and carries tracks registering 55 with tracks H^1 . When in position to receive and transfer the casket, which position is shown in Figs. 1, 2, 3, 4, its tracks form a continuation of the track H^1 , upon which the platform H^2 , carrying turntable F and 60 the casket, may be moved from its position upon the platform H , and out to the extremity of the platform H^3 . In order to facilitate removal the casket may be turned at right angles to the car where it would 65 assume the position shown in Fig. 4, when

the platform H^2 upon which it rests is moved outwardly for the purpose of taking the casket from the car. It is obvious that a reversal of these steps would enable the casket to be placed in the car; when so 70 placed the platform H^3 , may be elevated and form the lower part of the side wall of the car, which may be made to correspond substantially with the paneling in the car elsewhere. In each side of the opening is 75 formed a groove L , one of which is shown in Figs. 2 and 3; a corresponding groove, not shown, is in each of the opposite posts. There are also projecting pins illustrated at L^1 , extending from the platform and 80 engaging these grooves, the grooves being of the proper height and the pins being arranged in the platform H^3 , in the proper relation. It is obvious that by raising the outer edge of the platform the pins L^1 , slide 85 in the guiding grooves L , in the posts. The platform H^3 can be elevated perpendicularly and retained by appropriate bolts or latched in that position forming the side 90 of the car. Corresponding movable side walls L^3 , drop from the roof in a corresponding manner obtained by a similar construction, except that pins at either inner end of L^3 , at L^4 , engage in grooves L^5 , in the frame of the roof. By sliding the inner 95 ends outwardly with the lower ends resting upon proper bearings in the door-jambs, these upward partitions L^3 , may be dropped to meet the upward edge of the platform H^3 , when placed in a vertical position, and 100 in this manner the entire side of the car may be inclosed. It is obvious that the sliding pieces thus described may be made partly of glass or they may be paneled in wood and be perfectly opaque if desired. 105

For convenience in handling the casket I have provided a folding step M , as shown in Figs. 2 and 3, upon the right and left-hand side of those figures respectively, and as there is nothing new in folding steps 11 of this character it is unnecessary to describe them. It is obvious, however, that when the steps are folded, and the platforms H^3 , are raised to form the side of the car, as hereinbefore described, that the width of 11 the body of the car is reduced to its minimum degree which need not exceed substantially the length of the axles of the running gear upon which the car travels.

The operation of this device is obvious 1 from the foregoing description and it is not deemed necessary to further describe such operation.

Having thus described my invention what 1 I desire to claim is:

1. In a funeral car, the combination of a horizontally fixed platform, said platform being substantially narrower than the width of said car, ways fixed thereto at either end thereof at right angles to the axis of said

platform, a second platform adapted to engage said first named platform at its side and having thereon ways to correspond with and continue the ways on said fixed platform, means whereby said second platform may be elevated from a horizontal to a vertical position and form a part of the side of the car when in such vertical position, and adapted to return said second platform 10 to a horizontal position whereby the ways register with the ways upon the fixed platform, and the lower edge of said second platform is brought into the interior of the car, the upper edge thereof is extended 15 without the car, the dropping of said platform to this position simultaneously forming an opening in the side of the car, substantially as described.

2. In a funeral car, the combination of a 20 horizontally fixed rectangular platform, the longer axis corresponding with the axis of the car, ways fixed thereto at either end thereof at right angles to the axis of said platform, a second platform adapted to engage said first named platform at its side and having thereon ways to correspond and continue with the ways on said fixed platform, said second platform being adapted 25 to be raised and form a part of the side of the car when in a vertical position and when lowered in a horizontal position to afford ways continued to the outer wall of said car and simultaneously forming an opening 30 in the side of said car, a traveling platform having ways on its under side adapted to engage the ways hereinbefore described whereby said last named platform and its load may be transferred from the first 35 named platform to the second and out 40 through the side of the car, a turntable carried by said third platform, and a fourth platform adapted to fit and turn upon said turntable, and means for elevating and lowering the first named platform whereby said 45 platform may be raised above the level of the floor and lowered to said level, substantially as described.

3. In a funeral car, the combination comprising a compartment adapted to receive a casket, said compartment being readily 50 accessible from the outside of the car, and the bottom of said compartment being provided with parallel ways, a movable platform also provided with parallel ways adapted to register with the aforesaid parallel ways when said movable platform is in a horizontal position, said movable platform being adapted for elevation into a vertical position to constitute a part of the outside 55 walls of the car, and a casket carrier provided with means adapted to engage said parallel ways and adapted to travel thereon, whereby said casket when positioned on said carrier may be removed from within the car and out through the sides thereof 60 when said side walls are dropped to a horizontal position and the ways thereon are in register with the ways on the bottom of said casket compartment.

4. In a funeral car, the combination comprising a compartment adapted to receive a casket, said casket being readily accessible from outside of the car, a passenger compartment adjacent said casket compartment, partition means for separating said passenger compartment from said casket compartment, whereby observation of said casket when in said casket compartment from the passenger compartment may be prevented, movable closure means in the 75 wall of said casket compartment for admitting said casket therethrough when in an open position and adapted when closed to form a part of the side walls of the car, and means independent of said closure means 80 for permitting of independent access to said passenger compartment.

In testimony whereof, I sign this specification in the presence of two witnesses.

IDA SCHMIDT MARVIN.
